UNITED STATES PATENT OFFICE.

JOSEPH CHURCHILL ALFORD, OF MABEN, MISSISSIPPI.

SICKLE FOR MOWING-MACHINES AND THE LIKE.

1,231,111.

Specification of Letters Patent. Patented June 26, 1917.

Application filed November 13, 1916. Serial No. 131,128.

To all whom it may concern:

Be it known that I, JOSEPH C. ALFORD, a citizen of the United States, residing at Maben, in the county of Oktibbeha and State of Mississippi, have invented a new and useful Sickle for Mowing-Machines and the like, of which the following is a specification.

This invention relates to sickles for mowing machines and the like.

It is a well known fact that sickles as heretofore constructed with fastening rivets and the like extending through them often break because they are weakened where the rivet holes are formed in them.

One of the objects of the present invention is to provide a sickle the bar of which is imperforate, novel means being employed for securely holding the cutting teeth to the bar without necessitating the use of rivets as heretofore.

A still further object is to provide simple and efficient means for attaching the sickle head to the bar, it being possible readily to disconnect the several parts for the purpose of repairing or replacing them.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:

Figure 1 is a plan view of a portion of a sickle embodying the present improvements, parts being broken away.

Fig. 2 is a section on line 2—2 Fig. 1.

Fig. 3 is a section on line 3—3 Fig. 1.

Fig. 4 is a perspective view of one of the teeth.

Fig. 5 is a perspective view of one of the keys or locking strips.

Referring to the figures by characters of reference 1 designates the elongated bar of the sickle, the same being provided, at regular intervals, with upstanding lugs 2 extending transversely of the bar and with

additional upstanding lugs 3 interposed between the lugs 2 and likewise extending transversely of the bar, all of these lugs being substantially oblong in horizontal section. The back corner of each of the lugs 2 and 3 is chamfered, as shown at 4, while formed in the front face of each lug is a transverse recess 5 the bottom of which is in line with the top face of the bar 1. Formed transversely within the top of each of the lugs 2 and 3 is a dovetail groove 6 and these grooves are all in alinement. Said grooves are adapted to receive fastening keys in the form of dovetail strips 7 having their sides cut away or recessed at regular intervals as shown at 8. The keys are so proportioned that when they are inserted endwise through the grooves 6, they will become tightly seated within the grooves with the recessed or cut away portions located between the lugs as shown in Fig. 1. When the keys are thus positioned they rest upon the upper faces of teeth 9 of novel configuration. As shown in Fig. 4, each of these teeth has elongated recesses 10 in its side edges and is provided, midway between said recesses, with a slot 11. The depth of each of the recesses 10 is substantially equal to one-half the width of one of the lugs 2 and, consequently, when the teeth are assembled on the bar 1, each of the lugs 2 will be seated within recesses 10 in two opposed teeth and each lug 3 will project through a slot 11 in one of the teeth.

All of the lugs 2 and 3 on the bar are formed with transverse slots 6 except those lugs at one end of the bar where the sickle head 12 is to be attached. The lugs at this end of the bar are dovetailed in the direction of their length, as indicated at 13 and the cutter head 12 is provided with transverse dovetail grooves 14 adapted to receive the lugs 13. A recess 15 is formed in one end of the head 12 for the reception of the end of one of the locking strips 7.

When it is desired to assemble the parts of the sickle, the teeth 9 are placed in position between the pairs of lugs 2, the front walls of the recesses 10 being first inserted into the notches 5, after which the rear walls of the recesses are pressed downwardly so as to ride over the rounded corners 4 of the lugs until the teeth become firmly seated on the upper face of the bar 1. During this setting of the teeth the lugs 2 will

be under the slots 11 as will be apparent. The sickle head 12 is then shifted transversely over the lugs 13 so that said lugs will become snugly seated within the dovetail grooves 14. On completion of this adjustment of the parts, screws 16 or the like can be inserted into openings 17 in the ends of the sickle head 12 and into openings in certain of the lugs 13, thus to hold the sickle head against displacement. The locking strips 7 are then inserted longitudinally into the transverse recesses 6 in the lugs 2 and 3, this being done by bringing the cut away portions of the strips 7 above the slots 6, lowering them into the slots, and then shifting the strips longitudinally to bring the cut away portions into positions between the lugs. After the locking strips have thus been disposed, the one at the outer end can be secured by inserting a screw 18 into the bar 1 and up into the base of said strip 7 as shown particularly in Fig. 2. Thus all of the parts will be held together securely and will not become disconnected. Furthermore the bar 1 is not weakened by holes such as ordinarily provided and, as a result, a sickle such as herein described, will outlast those in common use. Obviously the various parts can be readily detached by reversing the operation hereinbefore described.

It is to be understood that one or more of the locking strips or keys 7 can be placed end to end, this being dependent upon the length of the sickle. In the drawings two of these locking strips or keys have been shown.

While screws 16 or the like are preferably employed for the purpose of holding the head 12 against withdrawal from the lugs 13, it is to be understood that that end of key 7 extending into the recess or socket 15 will operate as a means for preventing detachment of the head 12.

Indentations 7' may be provided in the upper edges of the keys 7 so that by inserting a punch into one of these indentations and inclining the parts toward one end or the other of the keys or locking strips the key 50 can be driven into or out of position. A slot 18' is formed longitudinally within the free end portion of the bar 1 for the reception of the screw 18.

What is claimed is:—

1. A sickle including a bar, spaced lugs upstanding therefrom and extending transversely thereof, each lug having a recess in its front end and having a chamfered rear end, teeth having side recesses for the reception of the lugs, the front ends of the recesses being insertible into the recesses in the lugs, and means engaging the lugs for holding the teeth upon the bar and between the lugs.

2. A sickle including a bar, upstanding

transverse lugs thereon, teeth engaging and interposed between the lugs, additional lugs upstanding from the bar and extending through the teeth, and means engaging the lugs for detachably securing the teeth upon the bar, said securing means and lugs having interfitting dovetail portions.

3. A sickle including a bar, lugs upstanding therefrom, teeth detachably mounted on the bar and interposed between the lugs, additional lugs upstanding from the bar and extending through the teeth, a head slidable into engagement with the lugs at one end of the bar and bearing upon the teeth therebetween, said head and lugs having interfitting portions, and a key insertible transversely into the lugs to bind the teeth thereunder to the bar, said head having a recess for the reception of one end of the key.

4. A sickle including a bar, lugs upstanding therefrom, teeth detachably mounted on the bar and interposed between the lugs, additional lugs upstanding from the bar and extending through the teeth, a head slidable into engagement with the lugs at one end of the bar and bearing upon the teeth therebetween, said head and lugs having interfitting portions, a key insertible transversely into the remaining lugs to bind the teeth thereunder to the bar, said head having a recess for the reception of one end of the key, and means for holding the key against movement relative to the bar.

5. A sickle including a bar, lugs upstanding therefrom, teeth detachably mounted on the bar and interposed between the lugs, additional lugs upstanding from the bar and extending through the teeth, a head slidable into engagement with the lugs at one end of the bar and bearing upon the teeth therebetween, said head and lugs having interfitting portions, a key insertible transversely into the remaining lugs to bind the teeth thereunder to the bar, said head having a recess for the reception of one end of the key, said key constituting means for holding the head against movement off of the lugs engaged therewith, and means for fastening the key to the bar.

6. A sickle including a bar, lugs upstanding therefrom, teeth interposed between the lugs and resting on the bar, additional lugs extending from the bar and through the teeth, said teeth having transverse grooves, keys insertible downwardly into the grooves, and means on the keys and shiftable longitudinally therewith into the grooves for holding said keys against upward withdrawal from the grooves.

7. A sickle including a bar, lugs upstanding therefrom, teeth interposed between the lugs and resting on the bar, additional lugs extending from the bar and through the teeth, said teeth having transverse grooves, keys insertible downwardly into the grooves,

means on the keys and shiftable longitudinally therewith into the grooves for holding said keys against upward withdrawal from the grooves, and means for holding the keys against movement relative to the bar and lugs.

In testimony that I claim the foregoing as

my own, I have hereto affixed my signature in the presence of two witnesses.

JOSEPH CHURCHILL ALFORD.
